UNITED STATES PATENT OFFICE.

NICHOLAS W. KYLE, OF COLFAX, ILLINOIS.

LIFTING DEVICE.

Application filed October 3, 1921. Serial No. 504,945.

To all whom it may concern:

Be it known that I, NICHOLAS W. KYLE, a citizen of the United States, residing at Colfax, in the county of McLean and State 5 of Illinois, have invented new and useful Improvements in Lifting Devices, of which the following is a specification.

This invention relates to lifting devices and is adaptable particularly to trucks, 10 wagons, elevator grain dumps, operating tables, etc., in fact, is adaptable to practically all types of devices wherein a tilting or movable body is employed.

The invention in the present instance is 15 an improvement over the device disclosed by my former patent dated October 25, 1898, No. 612,948; the improvement per se residing in the specific mechanism employed for causing the table or body to be raised 20 or lowered upon its support.

A particular object of the invention is to provide means of simplified and improved construction whereby the table or body may be quickly, easily and with smooth operation 25 raised or lowered the desired limit, and wherein a minimum amount of energy only is required in the performance of these operations.

A further object of the invention is to 30 provide apparatus of the character stated wherein the extensible means connecting the table or movable body with the rotor or power device is of light weight and capable of being manufactured and assembled 35 easily, and wherein the said parts collapse or fold properly one upon the other in neat and compact arrangement when the body is lowered, and which extend themselves automatically and in a smooth manner 40 when the rotor is operated so as to elevate the table or body.

With these and other objects in view, the invention consists of the features of construction, combination and arrangement 45 of parts, hereinafter fully described and claimed, reference being had to the accompanying drawings, in which:—

Figure 1 is a side elevation of an elevating or lifting device constructed in accordance with the invention, the view illustrating the same as applied to a conventional type of dumping truck, the elevating mechanism being shown in a position wherein the body of the truck has been raised to its extreme upward limit,

Figure 2 is a similar view and showing the truck body in a lowered position,

Figure 3 is a similar view showing the dumping body in an intermediate position,

Figure 4 is a similar view illustrating 60 the body in the course of being raised,

Figure 5 is an enlarged side elevation of the elevating or lifting device in extended position,

Figure 6 is a rear elevation of the same, 65 and

Figure 7 is a sectional view taken longitudinally through the elevating mechanism.

In the present illustration, for the purposes merely of describing the construction 70 and operation of the elevating device, the invention is shown as employed in connection with a vehicle truck of that character wherein the body thereof is tiltably mounted upon the frame or chassis so as to be 75 capable of dumping the load when required. It will be understood, however, that the elevating device may equally as well be used in connection with other types of dumping vehicles, tables, elevating devices 80 of various types, in fact, it may be successfully carried out in connection with most all types of devices wherein an elevating and lowering action of a body is 85 required.

In the drawing, 8 indicates the base or support, in the present instance the same including the side rails of the vehicle body, and 9 the line of the rear wall of the cab or house carried by the said chassis or 90 frame. 10 represents generally the tilting body to be elevated and lowered.

Mounted in suitable bearings upon the body 8, and preferably upon the side bars thereof, is a shaft 11, the latter being disposed transversely of the frame and being provided near one end with a worm gear 12, with which is associated a worm 13 operated by means of a crank 14. It will be understood, therefore, that as the crank is 100 rotated the worm 13 will operate upon the worm wheel 12 to rotate the shaft 11. This shaft is located upon the frame adjacent to the position which the free swinging end of the tilting body will assume when in 105 lowered position.

The shaft 11 has rigidly attached thereto a rotor indicated at 15. This rotor includes a pair of plates 16 of equal length, through the centers of which the shaft 11 110

extends, the latter being rigidly attached to the said plates. The plates are maintained in spaced parallel relation upon the shaft 11 and are connected to each other at their ends by cross members such as bolts indicated at 17. These bolts are spaced equidistant from the shaft 11.

The mechanism for elevating or lowering the body 10 includes a plurality of toggle levers being connected end to end the outer end of one extreme toggle lever being connected with the body 10, while the outer end of the other extreme toggle lever being pivotally connected with the rotor 15. In the present instance there are three of such toggle levers employed, the same being indicated at 18, 19 and 20. The toggle lever 18 is provided at one end with a head 21 of substantially circular formation, the said head including spaced annular plates as shown in Figure 6, and the opposite end of the said toggle lever comprises a pair of relatively smaller heads 22 spaced apart and pivoted upon one of the bolts 17 of the rotor 15. The head plates 21 are slotted inwardly from one side thereof as at 23, said slots being concentric with the pivotal connection of the said lever with the rotor 15, and the slots extending into the center of the circular heads 21. The central portions of head plates 21 are provided with annular openings 24 concentric with the said head plates, and which receive a rotary key member 25 carried by the inner end of toggle lever 19, the said toggle lever 19 including a pair of spaced plates of identical construction as shown in Figure 6 and fitting snugly but rotatably within the plates 21 of toggle lever 18. The lever 19, by reason of the rotary key connection between the inner end thereof and the outer end of the lever 18, pivots upon the said lever 18, and is limited in its swinging movement in one direction upon the said lever 18 by means of the pin or stud 26 carried by lever 19 engaging with shoulder 27 of lever 18. It will be noted that this limit of movement is reached when the rear straight walls of faces of levers 18-19 are in alinement with each other. A safety lock 28 is carried at the outer end of a leaf spring 29 secured to the rear flat face of link 18 engages within a recess 30 in the rear surface of toggle lever 18 when levers 18-19 are extended and assists in preventing the said levers moving further. When extended, as shown in Figures 5, 6 and 7, an arcuate slot 31 in the inner end of lever 19 alines with the arcuate slot 23 in the adjacent end of lever 18, the said slots being concentric with each other and of the same width and depth, the said slot 31 also passing into the rotary key 25.

The outer end of toggle lever 19 is provided with annular head members 32 of equal size and of identical construction with

the heads 21 of lever 18, being provided with arcuate slots 33 opening to one side of the head plates and spaced from the center of head 21 a distance equal between the center of the last mentioned head and the pivot 17 of plate or lever 18. The slot 33 is concentric with the center of head 21. Head plates 32 of lever 19 are provided with central key-pieces or annular openings 34 receiving annular shoulders 35 of the end toggle link 20, the latter being therefore capable of rotating upon head 32. The link or lever 20 fits snugly and rotatably between the spaced plates 32 at the outer end of lever 19, and is limited in its movement in one direction by engagement of the cooperating shoulders 36 at the rear of head 32 and lever 20. These shoulders come into abutment with each other only when the rear straight face of lever 20 alines with the corresponding face of lever 19. The spring catch member 29 engages within a suitable recess in the inner end of lever 20 to maintain the same latched in extended position. The outer end of link or lever 20 is provided with an opening 37 by means of which it is pivoted as by a pin 38 to a bracket 39 secured to the movable body 10 of the vehicle.

When the body 10 is elevated to its extreme raised position, as shown in Figure 1 of the drawings, the toggle levers 18-19-20 will be extended or longitudinally alined, and the centers of levers 19-18 will be alined with the pivot 17 with which the lever 18 is connected to the rotor 15. When so positioned, the rear straight faces of the toggle levers will be alined, the pin 27 will be engaged with the shoulder upon lever 18, the shoulders 36 of levers 19-20 will be engaged, and the latch members 28 carried by lever 19 will be engaged within the recesses in toggle levers 20 and 18. When it is desired to collapse the elevating mechanism, or, in other words, to lower the body 10, the crank handle 14 is rotated so as to move rotor 15 in counter-clockwise direction. As rotor 15 moves, the alined toggle levers 18-19-20 will move bodily downwards and when the pivot 17 to which lever 18 is connected reaches its lowest position, the pivot 17 at the opposite end of the rotor will pass into the alined slots 23-31 at the outer end of toggle lever 18. Continued counter-clockwise movement of rotor 15 then causes the joint between levers 18 and 19 to "break", and the lever 18 then remains collapsed upon or within the rotor 15. As the rotor further moves, the pin 17 to which lever 18 is pivoted will move up and into the alined slots 33 in the pivotally connected heads of levers 19 and 20, whereupon continued movement of the rotor will cause the joint between these levers to "break". The device then resumes the position shown in Figure 2 of the drawings, and in order to fully lower the body 10 the

shaft 11 is rotated a quarter turn in counter-clockwise direction, whereupon the body 10 will be brought down to rest upon the frame 8. In this manner, the toggle levers collapse 5 one upon the other and nest themselves in each other. To elevate the body, the crank 14 is rotated so as to turn rotor 15 in clockwise direction, whereupon the toggle levers 20—19—18 will be caused to extend or unfold one after the other in the order named, and it will be understood that as they reach "straightened" position, they will be locked 10 against further movement by means of the shoulders 36 and pin and shoulders 26—27. 15 This locking movement is assisted, furthermore, by the latch members 26 of spring leaves 29.

By constructing the elevating device in the manner mentioned, it is at once apparent 20 that a minimum amount only of exertion need be expended in raising and lowering the body 10. In the raising operation, the toggle levers will extend themselves one at a time until the lifting mechanism has been 25 fully unfolded, and by means of the worm and worm gear power drive, this operation is carried out with but slight exertion. In the lowering operation, the said levers fall and nest themselves one within the other in 30 regular order beginning with the inner toggle lever, and the said levers are so constructed and assembled as to properly nest without danger of overlapping or becoming disaligned and without danger of being 35 jammed. It will be understood, of course, that more or less numbers of toggle levers may be employed as occasion requires.

In order that the rotor may be brought to 40 a stop when the levers 18—19—20 have been fully extended, stop members 40 are secured to the plates 16 constituting the rotor 15 upon the inner sides thereof and adjacent to the inner annular ends of the plates constituting toggle lever 18. These stops are so 45 positioned and the inner end of toggle lever 18 is so shaped that they will come into engagement with each other immediately upon the lever 18 being properly extended, and these stops lock the rotor 15 and toggle member 18 against further relative movement to each other in the raising position.

While the above is a description of the 50 invention in its preferred embodiment, it is to be understood that various changes in the minor details of construction and arrangement of parts may be resorted to without departing from the spirit of the invention as defined by the claims.

Having thus fully described my invention, 55 I claim:

1. In a device of the class described, the combination of a support, a tilttable member, a rotor mounted on said support and including a pair of pins spaced equidistantly from the axis thereof and diametrically opposite

each other, a series of at least three toggle levers coupling said rotor to said tilttable member, the terminal levers being respectively pivoted at their outer ends to one of said rotor pins and the tilttable member and 70 pivotally connected at their inner ends with the ends of the intermediate toggle lever, the latter-named pivotal connections having slots therein, the distance between the pivotal connections of said levers to each other 75 being equal to the distance between the pins on said rotor, and the said slots in said pivotal connection adapted to receive and engage pins on said rotor, the construction being such that the levers are adapted to 80 swing outwardly in extended relation in alinement with each other and to collapse in nested arrangement with each other and the rotor, and means for transmitting motion to the rotor. 85

2. In a device of the class described, the combination of a support, a tilttable member, a rotor mounted on said support and including a pair of pins spaced equidistantly from the axis thereof and diametrically opposite each other, a series of at least three toggle levers coupling said rotor to said tilttable member, the terminal levers being respectively pivoted at their outer ends to one of said rotor pins and the tilttable member and pivotally connected at their inner ends with the ends of the intermediate toggle lever, the latter-named pivotal connections having slots therein, the distance between the pivotal connections of said levers 90 to each other being equal to the distance between the pins on said rotor, and the said slots in said pivotal connection adapted to receive and engage the pins on said rotor, the construction being such that the levers are adapted to 95 swing outwardly in extended relation in alinement with each other and to collapse in nested arrangement with each other and the rotor, a shaft on which the rotor is mounted, a worm gear on said shaft, 100 a worm engaging said gear, and means for operating said worm. 105

3. In a device of the class described, the combination of a support, a tilttable member, a rotor having a pair of pins spaced equidistantly from and on opposite sides of its axis, a series of at least three toggle levers coupling said rotor to said tilttable member, the terminal levers of said series being respectively pivotally connected at their outer ends to one of the pins of the rotor and to the tilttable member, the said terminal levers of the series being pivotally connected at 115 their inner ends with the inner ends of the intermediate toggle lever, and the latter-named pivotal connections having slots therein, said levers adapted to be extended in substantially longitudinal alinement and to fold upon their pivotal connections in nested arrangement with each other and with 120 125 130

the rotor, and the slots of the pivotal connections of the levers being adapted for engagement with the pins of the rotor when said parts are nested together, means for limiting the opening movements of the levers including spring locking members mounted upon the intermediate lever and adapted for

engagement with the adjacent ends of the terminal levers, a shaft carrying said rotor, a worm gearing on said shaft, a worm engaging said gear, and means for transmitting motion to said worm. ¹⁰

In testimony whereof I affix my signature.

NICHOLAS W. KYLE.
